UNITED STATES PATENT OFFICE.

KENNETH E. STUART, OF PHILADELPHIA, PENNSYLVANIA.

ELECTRIC-RAILWAY SYSTEM.

1,265,829.

Specification of Letters Patent. Patented May 14, 1918.

Application filed August 29, 1914. Serial No. 859,153.

To all whom it may concern:

Be it known that I, KENNETH E. STUART, a citizen of the United States, residing in the city of Philadelphia, Pennsylvania, have 5 invented new and useful Improvements in Electric-Railway Systems, of which the following is a specification.

My invention relates to automatically controlled electric railway systems suitable 10 for the carriage of mail, parcels, and for any other purposes, particularly where the motor cars are automatically controlled.

More particularly my invention relates to a system of the character described in my 15 prior patents numbered 1,150,902, 1,240,897 and 1,240,898, but characterized by the fact that the current for the operation of the cars or trains is derived from a plurality of generators or sources supplying current at 20 different voltages. And a further feature of my invention resides in an auxiliary brake, such as a friction brake, which comes into operation only after the car or train has been brought to rest by motor braking.

25 Another feature of my invention resides in means for automatic application of a brake when the current supply is interrupted.

Another feature of my invention resides in 30 an automatic block system for prevention of collision between cars or trains.

For an illustration of some of the forms my invention may take reference is to be had to the accompanying drawings, in which:

35 Figure 1 is an end elevation of an auxiliary brake as referred to above.

Fig. 2 is a cross-section through the same along the line 2—2 of Fig. 1.

Fig. 3 is a side elevation of a modified 40 design for the auxiliary brake.

Fig. 4 is an end elevation of a third design for the auxiliary brake.

Fig. 5 is a plan view of the same shown 45 partially sectioned along the line 5—5 of Fig. 4.

Figs. 6 and 7 are diagrams showing two arrangements of the connections between the motor on a car, the auxiliary brake and the contact conductors extending along the 50 trackway.

Fig. 8 is a diagram of the track at a terminal station together with the genera-

tors and the connections between the same and the track contact conductors and control apparatus.

Fig. 9 is a similar diagram for one block section complete.

Fig. 10 is a similar diagram for the station located at the opposite terminus of the line.

Figs. 11 and 12 are diagrams for the two alternative positions of the controllers for the braking section before a station.

Figs. 13, 14, 15, 16 and 17 are diagrams illustrating various methods of connecting 65 the several generators supplying the different voltages used in operating the system as mentioned above.

Referring now to Figs. 1 and 2, B represents brake mechanism of which W is a disk 70 wheel keyed to the end of the shaft S of the electric motor M. This wheel is preferably of phosphor bronze or other non-magnetic metal. Upon the inner side of the wheel near the rim is provided a machined 75 surface S₁, preferably coned as shown in the figure, and adapted to absorb energy through friction. A is a magnet armature of disk form, having machined upon it a surface adapted to fit the coned rubbing surface 80 of the wheel, and provided with the jaws J engaging the bolts B₁, which serve to keep the armature from turning.

The armature A is mounted upon a non-magnetic sleeve S₂ sliding freely in the barrel B₂ which forms part of the iron frame casting and is turned inside and outside concentrically with the shaft S. The barrel B₂ is wound with an energizing coil C. B₃ an outer barrel likewise forming part of the 90 frame casting, which serves to protect the coil and complete the iron magnetic circuit outside the coil.

Under normal circumstances the armature is pressed against the wheel W by a powerful spring S₃, exercising a braking effect upon it. In this position air gaps are opened at G₁ and G₂ as shown in the figure. When the coil is supplied with current at the proper voltage, however, the armature is 100 drawn away from the wheel, leaving it free to turn.

N, N are nuts upon the bolts B₁ by means of which the armature can be clamped out

of engagement with the wheel when desired. In Fig. 1 one of the nuts is removed to show the jaw more clearly. A ball bearing B_b and a ball thrust B_t may be provided.

5 In Fig. 3 a band brake B_4 is shown, adapted to operate upon the fly wheel W_1 and normally applied by the weight W_2 or in the alternative released by the energizing of the magnet M_1 .

10 In Figs. 4 and 5, the fly wheel or friction wheel W_3 is permanently clamped by the ring O so as to offer frictional resistance to its turning. On the motor shaft is keyed one member of the clutch C_1 , the other member 15 of which is keyed to the fly wheel W_3 . The clutch is normally held in the engaging position by the spring S_4 . In the alternative it is released by the action of the magnet M_2 .

15 The two modified forms of brake are given to show that my invention is in no wise limited to the particular form first described.

20 Referring now to Fig. 6, T_1 represents a contact conductor adapted to supply current through the collector shoe S_5 to the armature A_1 of the motor upon the car and T_2 a second contact conductor adapted to supply current through the collector shoe S_6 to the field winding F of the motor upon the car, the two track rails T_3 , T_4 serving 25 as the return conductor to which the current is led through the car wheel W_4 . F_1 represents a few compound series turns, which are desirable in a system of this kind 30 in order that when two or more motors are required to run together on one car or on a train any slight tendency of one to run faster than the other and take more than its share of the load may be counteracted 35 by the strengthening of its field due to these compound series turns.

40 B is the auxiliary brake above described. It will be noted that in Fig. 6 the brake coil is connected in shunt with the field, 45 so that the interruption of the armature current will not affect it, but interruption of the field current will cause it to be applied.

45 In Fig. 7 on the other hand, the coil of the auxiliary brake is connected in shunt with the armature so that failure of the supply to the armature will cause the brake to be applied. This is an alternative to the arrangement shown in Fig. 6, but for reasons 50 to be given later I prefer the arrangement first shown, in which the brake is released by current derived from the source supplying the motor field.

55 Referring to Figs. 8, 9 and 10, T_1 , T_2 and T_3 represent respectively, the armature contact conductor, the field contact conductor and the track rails (return conductor) as before. The direction of the traffic is indicated by the arrows. The return tracks, indicated by the dotted line, need not be considered.

60 The main feeder conductors 3, 4 and 5 extend throughout the length of the line. The conductor 3 is supplied with a voltage suitable for the operation of the trains at full speed, which will be hereinafter referred to as the full voltage. The conductor 5 is supplied with a voltage suitable for starting, which will be hereinafter referred to as the low voltage. The conductor 4 is supplied with an intermediate voltage.

65 G_2 , G_4 , G_5 form a generator set driven by a motor M_1 , to be more fully described later, which supplies the three voltages just mentioned to the mains 3, 4 and 5 and have their negative terminals connected together 70 and to either or both of the two track rails T_3 , T_4 . The generator G_3 comprises the shunt field winding G_{31} , the series field winding G_{32} and the armature G_{33} ; generator G_4 comprises the field winding G_{41} , excited at full voltage, the series field winding G_{42} and armature G_{43} ; the generator G_5 comprises field winding G_{51} excited at 80 full voltage, series field winding G_{52} and armature G_{53} ; and the motor M_1 comprises shunt field winding M_{11} , series field winding M_{12} and armature M_{13} .

75 I_1 , I_2 , I_3 , I_4 , etc., are insulators dividing the track and conductor rails into sections, the function of which will now be described.

80 The trains to be despatched are started from the section $I-I_1$ by means of a controller in the station (not shown). It should be borne in mind that, except when otherwise stated, the motor fields are constantly excited to full strength from the special contact conductor provided for that purpose. Passing over the section insulators I_1 (Fig. 8) the cars or trains enter a section upon which the armature is supplied through the 85 contactor K , to be hereafter described, with low voltage. Upon this section they are accelerated to the speed corresponding to the low voltage, at which speed they can safely take the intermediate voltage. Passing over the insulators I_2 , I_3 , they receive the intermediate voltage, and are accelerated to the speed at which they can take full voltage, by which time they reach the insulators I_4 , I_5 . Passing these insulators they receive 90 full voltage and are accelerated to full speed.

95 The short sections, as I_3-I_4 , receive current from the adjacent sections through rheostats R , which can be adjusted so as to 100 regulate the momentary rush of current which would otherwise occur as the trains passed on to a higher voltage.

105 Arriving at the second station (Fig. 10) the trains pass the insulators I_5 , I_6 and enter a section permanently supplied with intermediate voltage. As the motor fields are uniformly excited to full strength, the motors now become generators, and deliver current to the intermediate main, which 110

causes them to exert a powerful braking effect, until the speed of the train has been reduced to that corresponding to the voltage of this main. At this moment the trains 5 pass the insulators I_{10} , I_{10}' , enter a section permanently supplied from the low voltage main and are similarly braked down to the speed corresponding to the low voltage. Passing the insulators I_{11} , I_{11}' , the trains 10 now enter a section upon which the armature contact conductor is normally connected to the track, so that the armature is short-circuited, while the field continues at full strength. This causes the motor to continue 15 to exert a powerful braking effect so long as the train is in motion. Unless admitted to the station by the shifting of the controller C_2 , the train will now come to rest at C_3 (Fig. 10) where the presence of 20 a car is indicated by a diagram of the motor connections upon it.

It should be noted that the braking upon the sections I_9 — I_{10} and I_{10} — I_{11} is regenerative, *i. e.*, the energy given up by the trains 25 as their speed decreases is usefully applied to the driving of any other trains that may be accelerating upon the intermediate or low voltage mains, or even to the driving of the generators supplying these mains.

30 In the foregoing, the accelerating and braking of the trains has been described as taking place in three stages, but it is to be understood that a greater or less number of stages could be employed, depending upon 35 the overload capacity of the motors upon the cars.

In Fig. 10 the controller C_2 is shown in the braking position, in which, it will be seen, the section I_{11} — I_{12} of the armature contact conductor T_1 is connected to the track T_3 through the fingers 8 and 9. This is shown again in Fig. 11 to facilitate comparison with the alternative or starting position shown in Fig. 12, in which the armature 45 section will be seen to be connected through the finger 8 to the finger 7. In Fig. 10 it will be seen that the finger 7 is connected to the low voltage main. Hence to admit the train to the station the controller has 50 only to be shifted to the position shown in Fig. 12. The function of the fingers 6 and 10 will be explained later.

For the purpose of the automatic block system, the line is divided into block sections, and each block section is sub-divided so as to permit step-by-step braking when it is necessary to bring a train to rest in the block section and step-by-step acceleration in re-starting it, the braking and acceleration being accomplished as already described. Fig. 9 illustrates one complete block section extending between the insulators I_4 and I_5 and being sub-divided at I_5 , I_6 and I_8 . The section I_4 — I_5 which corresponds to the section I_9 — I_{10} , already de-

scribed, serves to brake the train down to the speed of the intermediate mains. Similarly, the section I_5 — I_6 corresponds to the section I_{10} — I_{11} , already described, and serves to brake the train down to the speed of the 70 low voltage main. Upon the section I_6 — I_8 , corresponding to the section I_{11} — I_{12} , the trains may be braked down from the low voltage speed to rest and re-started and accelerated to the low voltage speed. The section I_8 — I_9 may be compared with the section I_3 — I_4 , already described, upon which the trains are accelerated to intermediate speed, at which they may take full voltage upon 75 entering the next block section. 80

The sub-divisions of the block section are under control of the contactors K_1 and K^2 , which are shown diagrammatically. S_7 and S_8 are solenoids which when energized must be understood to draw the rod carrying the 85 contact disks each toward itself, establishing contact between the contacts P_1 , P_2 , etc., in a manner that will be obvious.

The sections I_4 — I_5 and I_8 — I_9 are connected to the contacts P_2 and P_4 . The corresponding contacts P_1 and P_3 are respectively connected to the full voltage and intermediate voltage mains. The section I_5 — I_6 is connected to the contacts P_6 and P_8 , the corresponding contacts P_5 and P_7 being connected respectively to the full voltage and low voltage mains. The section I_6 — I_8 is connected to the contacts P_{10} and P_{12} , the corresponding contacts P_9 and P_{11} being connected respectively to the section I_5 — I_6 and 100 to the track or negative conductor. 95

As shown in Fig. 9 the whole block section is closed, that is to say, in the position to bring the train to rest. It will be seen that in this position, which results from energizing the S_8 solenoids of both contactors, the first and second sub-sections are connected respectively to the intermediate and low voltage mains, the third is short-circuited and the fourth is connected to the intermediate voltage. A train arriving upon this block section will now be brought to rest at C_4 . In case it should for any reason be found impracticable in laying out the profile of the line to provide a level stopping 110 place at C_4 , the auxiliary brake B , already described, may now be brought into action. It will be seen that at this point a separate section of the field conductor rail is provided by means of the insulators I_7 , I_7' and 120 that this section is supplied through the contacts P_{13} , P_{14} . In the closed or braking position the connection between these contacts is interrupted, as in Fig. 9, leaving the field section I_7 — I_7' dead. This causes the coil C 125 of the auxiliary brake to be deenergized allowing the spring S_3 (Fig. 2) to apply the brake.

It will be apparent from the foregoing description that in any system of this kind it 130

is important that all the trains should stop at the same point in any block section, regardless of the load they carry, in order that they may start from the same point and pass off the sub-section at the same speed. Any system of braking by means of friction, however, depends upon a co-efficient that is extremely variable. Consequently, automatic friction braking would be very erratic. Moreover, under the same conditions a loaded train weighing twice as much as an empty train would go twice as far before coming to rest. Motor braking (*i.e.*, by short-circuiting the armature while the field is excited) on the other hand gives a perfectly definite and constant result which is to a certain extent self-regulating for different loads in the trains and can be made fully so by means described in my prior 20 patents numbered 1,240,897 and 1,240,898, filed, respectively, April 29, 1912 and May 1, 1912. Hence I use the auxiliary brake as little as possible and in fact only where the stopping point is unavoidably on a heavy 25 gradient, and then only as the trains are coming to rest.

It will now be understood why I prefer to connect the auxiliary brake in shunt with the motor field as in Fig. 3 rather than in 30 shunt with the armature as in Fig. 7, for in the latter case the brake would be applied as soon as the train arrived on the section I_6-I_8 , and cause the braking on this section to become erratic.

If now the contactor K_2 be operated by 35 energizing its S_7 solenoid, the armature contact conductor of the sub-section I_6-I_8 will be supplied with the low or starting voltage and the section I_1-I_2 of the field conductor 40 will be connected to full voltage. The other sub-sections will be unaffected. Hence the train will start and accelerating on the following sub-section, pass on.

If both the contactors K_1 and K_2 be operated by their S_7 solenoids, the entire block 45 section will be connected to the full voltage main.

The contactors are operated by means of the short contact rails T_1 , T_2 , etc., which are 50 placed along the trackway at the beginning of each block section, and between which and the negative track conductor circuit through solenoids S_8 of the contactors is momentarily established by the train in passing by 55 means of a contact arm carried upon the train, which it is not necessary to describe further. In the operation of the block system the trains in entering each block section automatically close the section they have 60 just vacated and open the section in the rear of the section just vacated.

Let us now suppose a train to be despatched from the first station, Fig. 8. In 65 passing the contact rail T_4 , it momentarily establishes connection by means of the wire

11 between the full voltage main, through the S_8 solenoid of the contactor K_1 , and the track or negative conductor, operating this contactor to close the section I_1-I_2 in the manner described.

Proceeding, the train passes the contact rail T_5 , closing the circuit through the S_8 solenoids of the contactors K_1 and K_2 , by means of the wire 12, and thus operating both these contactors to close this block section. But the wire 12 also has connection with the S_7 solenoid of the contactor K_2 , the function of which solenoid is to open the section I_1-I_2 . The current to energize this solenoid, is, however, not derived directly from the main, but must pass through the wire 13, and contacts P_{15} and P_{16} of the contactor K_2 (Fig. 9). But connection between these contacts is established only when the contactor K_2 is in the closed position. Hence the section I_1-I_2 cannot open until the next succeeding section has closed.

If allowed, the train will now come to rest at C_3 (Fig. 10) and if a second train is despatched it will stop at C_4 (Fig. 9) as indicated in the figure.

At C_4 a special short length of contact rail T_5 is provided, and while standing at this point the train establishes connection between this rail T_5 and the track as indicated in Fig. 9. To the rail T_5 is connected a wire 14 which closes a circuit from the main through the solenoid S_9 of the relay R_1 . This interrupts the connection between the contacts P_{15} .

If now the first train be brought into the station, in passing the contact rail T_7 (Fig. 10) it operates the contactor K_3 by energizing its solenoid S_8 to establish connection between the contacts P_{17} , P_{18} . These 105 contacts communicate through the wire 15 with the S_7 solenoid of the contactor K_2 , likewise when connection is established across the contacts P_{19} , with S_7 solenoid of the contactor K_1 . The current to energize these solenoids is derived, however, through the wire 16 and the fingers 6 and 10 of the controller C_2 , between which fingers there is connection only when the controller is in the braking position (see Figs. 11 and 12). After the first train has been brought into the station therefore, the second train will continue to be held up in the preceding block section until the controller C_2 is returned to its normal or braking position. 110 When this is done the S_7 solenoid of the contactor K_2 is energized, starting the second train.

If there had been no train on the block section when the first train was brought into the station it is obvious that both the contactors K_1 and K_2 would have been operated by their S_7 solenoids, relay R_1 being deenergized, thus placing the entire block section in the open or full voltage position.

The contactor K_3 is restored to its open position by energization of its solenoid S_7 by the next train passing the contact rail T_6 .

It will be obvious that although only one block section is shown, there can be any number upon the line according to its length.

If desired, an indication can be given in the stations as to whether any block section is open or closed by connecting to any part of each section that is normally connected to the current supply but cut off from the same when the section is closed, wires that are carried to both stations and connected through incandescent lights to the negative conductor. Thus all the lights will normally be lighted, but will be extinguished when their particular sections are closed.

Such lights are shown at L_1 , L_2 and L_3 , the connecting wires being 17, 18 and 19 respectively. The wires 17 and 18 are shown connected to the short sections of the field contact conductors I_2 , I_2 and I_7 — I_7 , respectively, while the wire 19 is shown connected to the section I_{11} — I_{12} of the armature contact conductor.

To insure in a system of this kind that the increments of voltage impressed upon the motor armature as the car passes off of one section to another shall not cause current flow exceeding the overload capacity of the motor armature it is important to preserve a constant ratio between the several voltages employed so that if one varies, they will all vary as nearly as possible in the same proportion. It is also necessary to avoid the possibility of one source reversing its polarity with reference to the others. These conditions are obtained by the hereinafter described arrangements.

In Fig. 13 two independent motor-generator sets are shown, driven by the motors M_3 and M_4 and taking current from the same source, which may be assumed to be the full voltage supply of the system described, while the two generators G_3 and G_4 supply the low and intermediate voltages respectively. The two generators are shown as self-exciting. Such an arrangement would be unsatisfactory as it does not fulfil the conditions laid down above. For example, a train regenerating on either of the motor generator sets would be likely to speed it up and raise the voltages of the whole main supplied by it relative to the other mains. Furthermore, it would be possible for any one of the generators to reverse its polarity relative to the others.

In Fig. 14 the two generators are shown mechanically driven by one motor. In Fig. 15 a third generator has been added, so as to make the set independent of earths in the original supply, and the fields are excited in series, so that reversing is impossible. In Fig. 16 the arrangement is similar to that

of Fig. 15 except that the fields are shown excited in shunt from the same supply, rendering reversing impossible as before. With either of the arrangements shown in Figs. 15 and 16 the speed of the motor M_5 would be likely to vary considerably with the load, thus lowering the voltage at all the mains. Furthermore, the voltage on each of the mains would be liable to drop under load through the line resistance. Hence in Fig. 8 differential series turns have been added to the motor and compound series turns to the generator. This is the preferred arrangement.

In Fig. 17 the three generators are connected in series. This permits them all to be wound for the same voltage, but does not enable them to be of one type, since under these circumstances the full voltage current would pass through all three generators, the intermediate current through two and the low voltage current through only one. Hence the intermediate voltage generator would be larger than the high voltage generator and the low voltage generator would be of still greater capacity than the other two.

It will be understood that as to various features of my invention it is not necessary that the different voltages be derived from separate sources of current as distinguished from a single source through graduated resistances.

And it will be further understood that various features of my invention are applicable to systems using either direct or alternating current for driving the car motors.

And it will be understood that my invention is not limited to the particular structures herein described for various equivalents of them are comprehended within the scope of my invention and will occur to those skilled in the art.

What I claim is:

1. In an electric railway system, the combination with a car, of a motor thereon, armature and field contact conductors extending along the path of travel of said car and divided into insulated sections for supplying current to the motor armature and field, respectively, means for supplying current to said contact conductor sections, electro-magnetic switching mechanism remaining in the position to which last actuated controlling connections between said current supplying means and said contact conductor sections, and contact elements placed at intervals along the path of travel and engaged by a car to control said electro-magnetic switching mechanism.

2. In an electric railway system, the combination with a car, of a motor thereon, a contact conductor extending along the trackway and divided into insulated sections for supplying current to said motor, sources

of current of different voltages, a contactor for controlling the connection of two of said sections with different of said sources, a relatively short intermediate section connected 5 through a resistance to one of said sections, whereby in one position of said contactor said motor has momentarily impressed upon it a voltage intermediate the voltages of said two of said sections, said contactor in another 10 position connecting said two of said sections to one of said sources of current.

3. In an electric railway system, the combination with a car, of a motor thereon, field and armature contact conductors extending 15 along the path of travel for supplying current to the field and armature of said motor, said armature conductor being divided into insulated sections, sources of current of different voltages connected to two of said sections, another of said sections being relatively short and disposed between said last mentioned sections and connected to one of them through a resistance, whereby the armature of said motor is in circuit with a 20 source of intermediate voltage.

4. In an automatic electric railway system, the combination with a car, of a motor thereon, a contact conductor extending along the path of travel of said car and 25 divided into sections, a plurality of conductors supplying current at different voltages extending along the path of travel of said car, and automatic switching mechanism for connecting different sections of said contact conductor to different of said supply conductors, the voltages impressed upon said sections of contact conductor diminishing in the direction of travel of said car, whereby when said car is on a section subjected to 30 lower voltage said motor operates as a generator to retard said car by delivering energy through said contact conductor to a supply conductor.

5. In an automatic electric railway system, the combination with a car, of a motor thereon, a contact conductor extending along the path of travel of said car and divided 45 into sections, a plurality of generators of current of different voltages, means mechanically coupling the rotating elements of said generators, switching mechanism connecting different sections of said contact conductor with different of said generators, said car when passing from a section of contact conductor of higher voltage to a section of lower voltage driving said motor as a generator to retard said car by delivering energy through said section of lower voltage to the corresponding generator, whereby the 50 remainder of said generators is assisted by said generator.

6. In an automatic electric railway system, the combination with a car, of a motor thereon, a contact conductor extending along 60 the path of travel of said car and divided

into sections, a plurality of conductors supplying current at different voltages extending along the path of travel of said car, and automatic switching mechanism for connecting different sections of contact conductor 70 to different of said supply conductors and for simultaneously connecting another section of said contact conductor in a motor braking circuit.

7. In an automatic electric railway system, the combination with a car, of a motor thereon, motor armature and motor field contact conductors extending along the path of travel of said car, a brake on said car, and a brake winding normally energized 30 from said field contact conductor for holding said brake inoperative.

8. In an automatic electric railway system, the combination with a car, of a motor thereon, motor armature and motor field contact conductors extending along the path of travel of said car, a brake on said car, and a brake winding normally energized 35 from said field contact conductor for holding said brake inoperative, said field contact conductor having a dead section for deenergizing said brake winding to set said brake.

9. In an automatic electric railway system, the combination with a car, of a motor thereon, motor armature and motor field contact conductors extending along the path of travel of said car, a brake on said car, a brake winding normally energized from 45 said field contact conductor for holding said brake inoperative, said field contact conductor having a dead section for deenergizing said brake winding to set said brake, and switching mechanism for energizing said dead section to lift said brake. 105

10. In an automatic electric railway system, the combination with a car, of a motor thereon, motor armature and motor field contact conductors extending along the path of travel of said car, a brake on said car, a 110 brake winding normally energized from said field contact conductor for holding said brake inoperative, said field contact conductor having a dead section for deenergizing said brake winding to set said brake, and automatic switching mechanism controlled by another car for reenergizing said dead section to lift said brake.

11. In an automatic electric railway system, the combination with a car, of a motor thereon, motor armature and motor field contact conductors extending along the path of travel of said car, a return contact conductor, means for dividing said armature and field contact conductors into sections, 120 means for connecting a section of armature contact conductor to said return conductor for bringing said motor into a braking circuit, a brake on said car, a brake winding normally energized from said field contact 125 conductor.

conductor to hold said brake inoperative, a dead section of said field contact conductor reached by said car when said motor is in a braking circuit, whereby said brake winding is deenergized and said brake is set.

12. In an automatic electric railway system, the combination with a car, of a motor thereon, motor armature and motor field contact conductors extending along the path of travel of said car, a return contact conductor, means for dividing said armature and field contact conductors into sections, means for connecting a section of armature contact conductor to said return conductor for bringing said motor into a braking circuit, a brake on said car, a brake winding normally energized from said field contact conductor to hold said brake inoperative, a dead section of said field contact conductor reached by said car when said motor is in a braking circuit, whereby said brake winding is deenergized and said brake is set, and means for opening said motor braking circuit and connecting its section of armature contact conductor to a source of voltage and for connecting said dead field conductor section to a source of voltage, whereby said brake is lifted and said motor started.

13. In an automatic electric railway system, the combination with a car, of a motor thereon, motor armature and motor field contact conductors extending along the path of travel of said car, a return contact conductor, means for dividing said armature and field contact conductors into sections, means for connecting a section of armature contact conductor to said return conductor for bringing said motor into a braking circuit, a brake on said car, a brake winding normally energized from said field contact conductor to hold said brake inoperative, a dead section of said field contact conductor reached by said car when said motor is in a braking circuit, whereby said brake winding is deenergized and said brake is set, and automatic switching mechanism controlled by another car for opening said motor braking circuit and connecting its section of armature contact conductor to a source of voltage and for connecting said dead field conductor section to a source of voltage, whereby said brake is lifted and said motor started.

14. In an electric railway system, a car, a motor thereon, an armature contact conductor extending along the path of travel of said car and divided into block sections, means for separately exciting the motor field, means associated with each block section for completing a braking circuit through said car for bringing said car to rest, means for automatically putting the block section in the rear in condition for bringing a car to rest, a circuit controlling said last named means, and a contact element adjacent the

trackway controlling said circuit and engaged by said car.

15. In an electric railway system, a car, a motor thereon, an armature contact conductor extending along the path of travel of said car and divided into block sections, means for separately exciting the motor field, means associated with one of said block sections for bringing a car to rest and for restarting the same, means for putting the second block section in the rear in condition for restarting the car, a circuit controlling said last named means, and a contact element adjacent the trackway of said one of said block sections for controlling said circuit and engaged by said car.

16. In an electric railway system, a car, a motor thereon, an armature contact conductor extending along the path of travel of said car and divided into block sections, means for separately exciting the motor field, means associated with each block section for completing a braking circuit through said car for bringing a car to rest and for restarting the same, means for automatically putting the block section in the rear in condition for bringing the car to rest, means for putting the second block section in the rear in condition for restarting the car, a circuit controlling said two last named means, and a contact element adjacent the trackway for controlling said circuit and engaged by a car.

17. In an electric railway system, a car, a motor thereon, a subdivided armature contact conductor extending along the path of travel of said car for supplying current to the armature of said motor, means for separately exciting the motor field, a return contact conductor, a contactor, a source of current, said contactor in one position connecting a subdivision of said contact conductor with said source of current and in another position connecting said subdivision of contact conductor with said return conductor, a circuit controlling said contactor, and a contact controlling said circuit and engaged by a car.

18. In an electric railway system, a car, a motor thereon, subdivided armature and field contact conductors extending along the path of travel of said car for separately supplying current to the motor armature and field, and automatic switching mechanism controlled by another car for simultaneously isolating a section of armature contact conductor and a section of field contact conductor, said switching mechanism in another position reenergizing said field and armature sections at full voltage and low voltage, respectively.

19. In an electric railway system, a car, a motor thereon, a subdivided contact conductor extending along the path of travel of said car, a plurality of sources of current

- of different voltages, a contactor in one position connecting sections of said contact conductor to the source of current of highest voltage and in another position connecting 5 said sections of contact conductor to sources of current of different voltages, and coöperating contacts disposed on said car and in its path of travel for controlling said contactor.
- 10 20. In an electric railway system, a car, a motor thereon, a subdivided contact conductor extending along the path of travel of said car, a plurality of sources of current of different voltages, a contactor in one position 15 connecting sections of said contact conductor to the source of current of highest voltage and in another position connecting said sections of contact conductor to sources of current of different voltages, and a plurality 20 of contacts disposed at different distances along the path of travel of said car and engaged in succession by said car controlling said contactor.
21. In an electric railway system, a car, a 25 motor thereon, a subdivided contact conductor extending along the path of travel of said car, a plurality of sources of current of different voltages, a contactor in one position connecting sections of said contact 30 conductor to the source of current of highest voltage and in another position connecting said sections of contact conductor to sources of current of different voltages, a return contact conductor, a second contactor for connecting a section of said contact conductor to 35 said return conductor for braking said motor, and coöperating contacts controlling said contactors and disposed on a car and in its path of travel.
- 40 22. In an electric railway system, a car, a motor thereon, a subdivided contact conductor extending along the path of travel of said car, a plurality of sources of current of different voltages, a contactor in one position 45 connecting sections of said contact conductor to the source of current of highest voltage and in another position connecting said sections of contact conductor to sources of current of different voltages, a return contact 50 conductor, a second contactor for connecting a section of said contact conductor to said return conductor for braking said motor, a contact controlling said contactors and engaged by a car, said second contactor having 55 a second position for connecting said section of contact conductor with one of said sources of current, and a second contact engaged by a car controlling said second contactor to take said second position.
- 60 23. In an electric railway system, a car, a motor thereon, subdivided armature and field contact conductors extending along the path of travel of said car, a contactor for connecting sections of said armature contact conductor to a source of current, a sec- 65 ond contactor for connecting another section of said armature contact conductor in a motor braking circuit and for isolating a section of field contact conductor, said second contactor having another position in 70 which said sections of armature and field contact conductors are supplied with current, a circuit for controlling said contactors for connecting said sections of contact conductor with said source of current, and means for preventing control of said first contactor by said circuit when said second contactor is in its motor braking position and the car has been braked thereby. 75
24. In an electric railway system, the combination with a car, a motor thereon, a subdivided contact conductor extending along the path of travel of said car, a plurality of sources of current of different voltages, means for connecting different sections 80 of contact conductor with sources of current of different voltages, and a resistance connecting sections of contact conductor subjected to different voltages. 85
25. In an electric railway system, a car, a motor thereon, a subdivided contact conductor extending along the path of travel of said car for supplying current to said motor, a plurality of sources of current of different voltages, and switching mechanism for connecting neighboring sections of said contact conductor with different of said sources of current, whereby the voltages impressed upon 90 said sections decrease in the direction of travel of said car, for connecting a succeeding section in a motor braking circuit or to one of said sources of current of low voltage, and a succeeding section to one of said sources of current of higher voltage, or for connecting all said sections to one of said 95 sources of current. 100
26. In an electric railway system, a car, a motor thereon, a subdivided contact conductor extending along the path of travel of said car for supplying current to said motor, a plurality of sources of current of different voltages, and automatic switching mechanism controlled by another car for connecting neighboring sections of said contact conductor with different of said sources of current, whereby the voltages impressed upon 110 said sections decrease in the direction of travel of said car, for connecting a succeeding section in a motor braking circuit or to one of said sources of current of low voltage, and a succeeding section to one of said sources of current of higher voltage, or for connecting all said sections to one of said 115 sources of current. 120
27. In an electric railway system, a car, a motor thereon, a subdivided contact conductor extending along the path of travel of said car, a controller associated with a section of said contact conductor for bringing the same into a motor braking circuit or con- 125 130

necting the same with a source of energy, a circuit closed by said controller when in braking position, a contactor controlling another section of said contact conductor controlled by said circuit, a second contactor controlling said circuit, and a car controlled contact controlling said second contactor.

28. In an electric railway system, a car, a motor thereon, a subdivided contact conductor extending along the path of travel of said car, a controller associated with a section of said contact conductor for bringing the same into a motor braking circuit or connecting the same with a source of energy, a circuit closed by said controller when in braking position, a contactor controlling another section of said contact conductor controlled by said circuit, a second contactor controlling said circuit, a car controlled contact controlling said second contactor to close said circuit, and a second car controlled contact controlling said second contactor to open said circuit.

29. In an electric railway system, a car, a motor thereon, a subdivided contact conductor extending along the path of travel of said car, a controller associated with a section of said contact conductor for bringing the same into a motor braking circuit or connecting the same with a source of energy, a circuit closed by said controller when in braking position, a contactor controlling another section of said contact conductor controlled by said circuit, a second contactor controlling said circuit, and a car controlled contact controlling said second contactor to close said circuit, said first named contactor controlling a section of contact conductor for motor braking a car to rest, and a third contactor controlling a section of contact conductor in the rear of said last named section, said last named contactor adapted to be controlled by said circuit.

30. In an electric railway system, a car, a motor thereon, a subdivided contact conductor extending along the path of travel of said car, a controller associated with a section of said contact conductor for bringing the same into a motor braking circuit or connecting the same with a source of energy, a circuit closed by said controller when in braking position, a contactor controlling another section of said contact conductor controlled by said circuit, a second contactor controlling said circuit, a car controlled contact controlling said second contactor to close said circuit, said first named contactor controlling a section of contact conductor for motor braking a car to rest, a third contactor controlling a section of contact conductor in the rear of said last named section, said last named contactor adapted to be controlled by a branch of said circuit, and means for opening said branch of said

circuit when a car has been brought to rest by said first named contactor.

31. In an electric railway system, a car, a motor thereon, a subdivided contact conductor extending along the path of travel 70 of said car, a controller associated with a section of said contact conductor for bringing the same into a motor braking circuit or connecting the same with a source of energy, a circuit closed by said controller 75 when in braking position, a contactor controlling another section of said contact conductor controlled by said circuit, a second contactor controlling said circuit, a car controlled contact controlling said second contactor to close said circuit, said first named contactor controlling a section of contact conductor for motor braking a car to rest, a third contactor controlling a section of contact conductor in the rear of said last named 80 section, said last named contactor adapted to be controlled by said circuit, and a second car controlled contact controlling said second contactor to open said circuit.

32. In an electric railway system, a car, 90 a motor thereon, a contact conductor extending along the path of travel of said car and divided into block sections, a plurality of sources of current of different voltages, automatic means associated with a block 95 section for retarding the car by connecting said motor to a source of lower voltage, for electro-dynamically braking said motor, and for restarting said motor by connecting said motor to a source of current of lower 100 voltage, a circuit controlling said automatic means, and a contact controlling said circuit and engaged by a car.

33. In an electric railway system, a car, a motor thereon, a contact conductor extending along the path of travel of said car and divided into block sections, a plurality of sources of current of different voltages, automatic means associated with a block section including means for retarding the 110 car by connecting said motor to a source of lower voltage, means for electro-dynamically braking said motor, and means for restarting said motor by connecting said motor to a source of current of lower voltage, a circuit controlling said automatic 115 means, a contact controlling said circuit and controlled by a car, said sources of current consisting of generators, and means for mechanically coupling the rotating elements 120 of said generators.

34. In an electric railway system, the combination with a car, a motor thereon, a subdivided contact conductor extending along the path of travel of said car, a plurality of dynamo-electric generators having their rotating elements mechanically coupled, automatic means for connecting different sections of said contact conductor to the generator of highest voltage or to gen- 125 130

- erators of lower voltage, said generators of lower voltage having field windings subjected to the voltage of the generator of highest voltage.
35. In an electric railway system, the combination with a car, a motor thereon, a subdivided contact conductor extending along the path of travel of said car, a plurality of dynamo-electric generators having their rotating elements mechanically coupled, automatic means for connecting different sections of said contact conductor to the generator of highest voltage or to generators of lower voltage, said generators of lower voltage having field windings subjected to the voltage of the generator of highest voltage, said generators having series field windings.
36. In an electric railway system, a car, a motor thereon, a subdivided contact conductor extending along the path of travel of said car, a plurality of mechanically coupled generators of current of different voltages, supply conductors extending from said generators along the path of travel of said car, and a car controlled contactor for connecting sections of said contact conductor to the supply conductor of highest voltage and in another position to supply conductors of lower voltage.
37. In an electric railway system, a car, a motor thereon, a subdivided contact conductor extending along the path of travel of said car, a plurality of generators of current of different voltages, supply conductors extending from said generators along the path of travel of said car, a car controlled contactor for connecting sections of said contact conductor to the supply conductor of highest voltage and in another position to supply conductors of lower voltage, and a second car controlled contactor in one position connecting a section of contact conductor in a motor braking circuit and in another position connecting said section of contact conductor to a supply conductor of lower voltage through said first contactor.
38. In an electric railway system, a car, a motor thereon, a subdivided contact conductor extending along the path of travel of said car, a plurality of generators of current of different voltages, supply conductors extending from said generators along the path of travel of said car, and a car controlled contactor for connecting sections of said contact conductor to the supply conductor of highest voltage and in another position to supply conductors of lower voltage, a second car controlled contactor in one position connecting a section of contact conductor in a motor braking circuit and in another position connecting said section of contact conductor to a supply conductor of lower voltage through said first contactor.
39. In an electric railway system, a car, a motor thereon, a subdivided contact conductor extending along the path of travel of said car, a plurality of generators of current of different voltages, supply conductors extending from said generators along the path of travel of said car, and a car controlled contactor for connecting sections of said contact conductor to the supply conductor of highest voltage and in another position to supply conductors of lower voltage, a second car controlled contactor in one position connecting a section of contact conductor in a motor braking circuit and in another position connecting said section to the supply conductor of highest voltage.
40. In an electric railway system, the combination with track sections, of cars, motors thereon, a contact conductor extending along the trackway and divided into insulated sections for supplying current to the car motors, a contactor for bringing one of said sections into a braking circuit to bring a car to rest, a second contactor for controlling current supply to a section of said contact conductor in advance of said braking section, a controller associated with another section of said contact conductor and controlling said contactors, a contact controlled by a car brought to rest by said braking section, and means controlled by said contact interrupting the control of said second contactor by said controller.
41. In an electric railway system, the combination with a car, of a motor thereon, motor armature and field contact conductors extending along the path of travel of said car, a return contact conductor, means for dividing said armature and field contact conductors into sections, means for connecting a section of armature contact conductor to said return conductor for bringing the motor armature into a braking circuit while the motor field is excited from said field contact conductor, a supplemental brake on said car, and a winding on said car controlling said brake and connected with said field contact conductor.

In testimony whereof I have hereunto affixed my signature in the presence of the two subscribing witnesses.

KENNETH E. STUART.
